A. T. McWANE

WINDOW GUARD

Filed July 6, 1926

Attorney

UNITED STATES PATENT OFFICE.

ARTHUR T. MCWANE, OF BIRMINGHAM, ALABAMA.

WINDOW GUARD.

Application filed July 6, 1926. Serial No. 120,598.

My invention relates to guards for the protection of windows and contemplates the utilization of demountable bars associated with means for mounting and locking the bars in operating position and with means for storing the bars when not in service.

One object of my invention is to design the mounting means for the bars so that the same are hardly noticeable and require but a slight change in the meeting check rails of the top and bottom sashes to receive them when applied to existing windows, and which are capable of being built into new window frames so as to take the place of the parting strip between the runways for the upper and lower sash.

Another object of my invention is to provide these bar mounting members with racks to receive and hold the demounted bars at the bottom of the window.

A further object is to design the bars so that they can be readily interlocked with their mounting members by the operation of one common lock bar and when thus locked in position, access cannot be had to unlock same without breaking the window.

My invention further comprises the novel details of construction and arrangements of parts, which in their preferred embodiment only, are illustrated in the accompanying drawings which form a part of this specification, and in which:

Fig. 1 is a front elevation with a window frame equipped with my improved guide bars shown in operating position and in demounted position in dotted lines.

Fig. 2 is a cross-sectional view taken on the line 2—2 of Fig. 1.

Fig. 3 is an enlarged view broken away of the bars showing their mounting means partly in elevation and partly in section.

Figs. 4 and 5 are detail views illustrating the latch for holding the lock bar in operation or idle position.

Similar reference numerals refer to similar parts throughout the drawings.

In the embodiment of my invention illustrated, I show conventionally a window frame having an upper sash 1, a lower sash 2, with the runways for said sashes separated by a parting strip 3 throughout their upper portions and by the bar mounting members 7 and 8 which continue to the stool 6 of the window frame. The bottom check rail 4 of the upper sash and the top check

rail 5 of the lower sash are cut away at each end, where necessary, to accommodate the members 7 and 8, such cutting being necessary where the guard is applied to old windows, but it may be avoided in new windows by having the mounting members 7 and 8 to correspond in cross section with the parting strip.

The bar mounting member 8 is preferably formed of tubular metal having the width of the parting strip 3 and having substantial depth so that the apertures 9, arranged at suitably spaced intervals in its inner edge, are adapted to receive the reduced ends 10 of the guard bars 11 with sufficient overlap of said ends in the mounting member to prevent them being pulled out. This tubular member 8 is secured in any desirable manner to the window frame as by wood screws 12 inserted through the apertures 9 and through the inner wall of the member and screwed into the window frame.

The mounting member 7 for the other end of the bars is also formed of tubular metal similar in cross section to the member 8 and similarly mounted. At corresponding intervals in this member 7 opposite the apertures 9 I provide notches 13 which extend from the outside wall across the inner end wall and partway across the inside wall, thus permitting the ends 14 of the rods to be moved into position with the holes 15 in such ends disposed in alignment within the tubular member 7. In the space between the ends 14 of the bars and the inner wall of the member 7 which is screwed to the frame, I introduce a lock bar 16 having for each bar 11 an offset downturned angled lock pin 17 adapted to project through the hole 15 in its respective bar. The upper end of this lock rod is out-turned at 18 and adapted to engage in one or the other of two holes 19 or 20 in a plate 21 attached to the parting strip 3, these holes permitting the lock bar to be set in operative or inoperative position.

At the bottom of the members 7 and 8 I provide means to rack the dismounted guard bars 11, such means preferably taking the form of an inside notch 22 merging into a vertical slot 23 in the inner edge of the member 8 at its base, and a vertical slot 24 at the base of the inner wall of the member 7. By this arrangement the bars 11, as they are dismounted, can have their ends 14 inserted in the slot 24 and their other ends in

2
serted through the notches 22 and dropped down into the slot 23, thus providing a rack for the bars.

Having attached the mounting members 7, 5 and 8 to the window frame in the manner described, the guard bars 11 are put in place by inserting their reduced ends 10 in the apertures 9 in the mounting member 8 and then shifting the end 14 of each through a 10 notch 13 into position to register with the lock pins 17 of the lock bar, which at the time will be engaged in the upper hole 20, which holds it in inoperative position. When all of the bars 11 have been thus as- 15 sembled, the lock bar is disengaged from the upper hole 20 by bending it outwardly and then it is moved downwardly until the pins 17 interlock in the holes 15 of the several bars 11, after which the lock bar is en- 20 gaged in the lower hole 19 which prevents it from being raised by anyone on the outside of the window without breaking the glass.

This arrangement thus permits the bars to be readily put up at night and taken 25 down and racked during the day when they might be objectionable or unsightly.

Having thus described my invention, what I claim as new and desire to secure by Letters Patent, is:—

30 1. A window guard comprising a plurality of bars and mounting elements for said bars disposed in the plane of the parting strip between the window sashes, said elements comprising sockets to receive the ends 35 of the bars, and a locking device housed in

one of said elements and movable into position to lock or release all of said bars simultaneously, said bar mounting elements being provided at their bases with rack means to hold the dismounted guard bars. 40

2. A window guard comprising a plurality of separate bars and mounting elements therefor comprising at one side an element provided with apertures to receive one end of the bar and at the other side with a tubular element having notches for the reception of the other end of the bars, and a multiple lock bar for all of the guard bars slideable in said tubular element, the multiple lock bar projecting above the tubular element and lower sash and being associated with means on the parting strip to hold it in operative or inoperative position. 45 50

3. A window guard comprising a plurality of bars, each reduced at one end and at the other end flattened and perforated, a tubular bar support adapted to be mounted at each side in the plane of the parting strip, one bar support having holes in its inner wall to receive the reduced end of the guard bars and the other support having notches in its inner side and inner end wall to receive the flattened end of the guard bars, and a multiple lock element vertically slideable in said latter support and adapted to project through the perforations in the ends of the guard bars to lock them in assembled position in the bar supports. 55 60 65

In testimony whereof I affix my signature.
ARTHUR T. MCWANE.
